(57) **CLAIM**

The ornamental design for an electronic animal call, as shown and described.

DESCRIPTION

FIG. 1 is a perspective view of the electronic animal call; FIG. 2 is a front view of the electronic animal call; FIG. 3 is a back view of the electronic animal call; FIG. 4 is a side view of the electronic animal call; FIG. 5 is a top view of the electronic animal call; and, FIG. 6 is a bottom view of the electronic animal call. The broken lines in the drawings depict portions of the electronic animal call that form no part of the claimed design.
